UNITED STATES PATENT OFFICE.

QUIMBY S. BACKUS, OF HOLYOKE, MASSACHUSETTS.

BIT-STOCK.

SPECIFICATION forming part of Letters Patent No. 250,047, dated November 29, 1881.

Application filed December 2, 1879.

To all whom it may concern:

Be it known that I, QUIMBY S. BACKUS, of Holyoke, in the county of Hampden and State of Massachusetts, have invented a new and useful Improvement in Ratchet-Braces; and I do hereby declare that the following specification, taken in connection with the accompanying drawings, forming a part of the same, is a full, clear, and exact description thereof.

My brace, like others heretofore well known, is capable of use as a right-hand or a left-hand ratchet-brace, or as an ordinary fixed or rigid brace; and my improvement consists in the particular means employed for controlling and adjusting the pawl, as hereinafter fully described and claimed.

Referring to the drawings, Figure 1 shows, in elevation and partial section, a portion of a brace embodying my improvement. Figs. 2 and 3 represent a portion of said brace in horizontal section on the line *x*. Fig. 4 shows, in perspective, the device employed to work the spring-pawl for adjusting it in different positions; and Fig. 5 represents said pawl in perspective.

As shown in Figs. 1, 2, and 3, A denotes a portion of the stock of the brace; B, the head into which it is screwed and to which it is secured, and C the device for gripping the bit or other tool, which device is mounted on a spindle, D, passing through a portion of said head B.

Secured to the spindle D is a ratchet, E, which occupies a slot, *b*, in the head B, and engaging this ratchet by the force of a spring, F, is a spring tooth or pawl G. The pawl G is of the form shown at Fig. 5. Its body is cylindrical, and it is mounted so as to turn freely in a cylindrical recess or chamber in the head B. In the same chamber, and at the rear end of the pawl, is located the spring F, as shown at Fig. 1. The front end of the pawl G is formed into a tooth, G', of rectangular cross-section at the base. It has two parallel sides, *g*, a side, *g'*, at right angles thereto, and a beveled face, *g*², as shown in Fig. 5. It is obvious that when the spring-pawl is so turned in its socket or bearing in the head-stock of the brace that its two parallel sides *g*, *g'* are engaged with the ratchet-wheel E the brace will be a stiff one. When, however, the spring-pawl is turned ninety degrees of a circle to the right or to the left the beveled face *g*² of the

spring-tooth will be in relation to the teeth of the ratchet, either as shown at Fig. 2 or at Fig. 3, and the brace will become either a right-hand or a left-hand ratchet-brace.

The device by which the spring-pawl G is worked is shown at Fig. 4. It consists, in this instance, of a sleeve or collar, H, arranged concentric with the pawl and secured thereto by means of the pin J, and the upper half of the head or stock of the brace in the vicinity of the pin is cut away sufficiently to allow the collar so attached to the spring-pawl to be moved for a short distance backward and forward, and also to be rotated through the half of a circle. The arrangement of the collar, the spring-pawl, and the connecting-pin is shown at Figs. 1, 2, and 3.

To lock the spring-pawl in its several positions the edge of the collar H is furnished with three notches, *h*, Fig. 4, and there is inserted in the head-stock a stud-pin, K, Fig. 1. The positions of the notches in the collar correspond with the three positions of the spring-pawl exhibited in Figs. 1, 2, and 3, and when any one of such notches is engaged with the pin the pawl is held in the corresponding position and the brace is a stiff brace, a right-hand or a left-hand brace, as the case may be.

To manipulate the brace it is only necessary to slide the collar H backward until the notch is clear of the stop-pin K, then rotate the collar to the right or to the left, thereby correspondingly rotating the spring-pawl, and when the desired point is reached allow the spring F to project the spring-pawl into engagement with the ratchet-wheel and the corresponding notch in the collar to engage with the holding-pin.

What I claim as my invention, and desire to secure by Letters Patent as an improvement in bit-braces, is—

In a ratchet-brace, the combination, with the ratchet-wheel and the sliding spring-pawl, of the rotating and sliding collar H, connected with said pawl and provided with the stop-notches *h* for engaging with the stop-pin K and securing said pawl in either of its various working positions, substantially as described.

QUIMBY S. BACKUS.
